W. H. ROBBINS

STEEL WOOL MACHINE

Filed June 5, 1925

FIG. 1.

FIG. 2.

INVENTOR

WILLIAM H. ROBBINS,

By *Paulmin* *Paulmin*,

ATTORNEYS

UNITED STATES PATENT OFFICE.

WILLIAM H. ROBBINS, OF SPRINGFIELD, OHIO, ASSIGNOR TO THE WILLIAMS COMPANY, OF LONDON, OHIO, A CORPORATION OF OHIO.

STEEL-WOOL MACHINE.

Application filed June 5, 1925. Serial No. 35,156.

To all whom it may concern:

Be it known that I, WILLIAM H. ROBBINS, a citizen of the United States, residing at Springfield, in the county of Clark and State of Ohio, have invented certain new and useful Improvements in Steel-Wool Machines, of which the following is a specification, reference being had therein to the accompanying drawing.

10 My invention relates to steel wool and in particular to making steel wool blankets or pads.

15 It is the object of my invention to provide a method and means of manufacture of steel wool pads so that the resulting product may be formed into a pad or blanket of uniform thickness and density in a desired form.

20 The primary problem in forming steel wool blankets or pads is to insure uniform and adequate density of the product. It is my object to provide a method and means of so forming the steel wool blanket or pad that it may have this uniform density so that the product will be satisfactory and so that 25 an unnecessary amount of wool may not be wastefully included in the blanket or pad.

25 It is also highly desirable to have the density uniform when such pads are used for filtering or other purposes of similar character where uniformity in texture and density is essential.

Referring to the drawings:

Figure 1 illustrates in section my apparatus for effecting the purpose of my invention by indirect light;

Figure 2 is a similar view showing an apparatus for effecting the same purpose through direct light.

Referring to the drawings in detail, 1 is the side wall of a supporting frame or box provided with a bottom 2 in which is located on the upper surface thereof a reflecting surface 3. The upper edges of the walls 1 carry an inwardly extending ledge 4 from which are angularly disposed in a depending position the lighting brackets 5 having reflectors 6 and incandescent electric bulbs 7. On the top of this ledge 4 and positioned by the shoulder 8 is a transparent plate of glass 9. This plate may be translucent or ground glass if desired. The steel wool is placed in a frame 10 as at 11 over the glass 9. It is moved within this frame

until the pad or blanket is of the density desired. This can be determined by the operator by observing the amount of light which is reflected from the lamp 7 by the surface 3 through the glass 9, passing through the steel wool 11. By re-arranging the wool until the passage of light therethrough is substantially uniform, a resulting equal density of the steel wool pad or blanket is secured, the outside configuration of which is determined by the frame 10.

If it is desired to have direct lighting, 65 then the lamps 7 are located as in Figure 2 on the bottom of the housing which is marked 2 and the light direct upwardly by the reflectors 6 and lamp 7 through the supporting glass plate 9 through the steel wool 70 blanket 11.

It will be understood that I desire to comprehend within my invention such modifications as may be necessary to adapt it to varying conditions and uses.

Having thus fully described my invention, what I claim as new and desire to secure by Letters Patent, is:

1. In combination, a casing, a top therefor adapted to pass light therethrough, a source of light within said casing to project light through the top, and a frame mounted on the top of said casing to contain steel wool.

2. In combination, a casing, a light-reflecting interior, and a light-passing medium forming the top of said casing, whereby steel wool located on said top may be arranged to have equal density throughout the mass by so arranging the wool that the light will pass therethrough equally at all points, and a frame adapted to be mounted on the surface of said top for maintaining the margins in position to give the wool a proper marginal configuration.

3. In combination, a casing, lamps suspended around the margin of the top with reflectors on said lamps reflecting the light downwardly to the inside of the bottom of the casing, a light reflecting bottom, a top adapted to pass light therethrough, and adapted to support steel wool on the outside thereof.

In testimony whereof I affix my signature.

WILLIAM H. ROBBINS.
